PHONOGRAPH NEEDLE

Wiley D. Wenger, Shenandoah, Iowa

Application June 12, 1933, Serial No. 675,446

3 Claims. (Cl. 274—38)

This invention relates to the phonographic art and more particularly to a method and means for recording human speech and other sounds upon a record having particular characteristics 5 adapted to be used in conjunction with a novel reproducing means.

An object of this invention is to provide an improved construction of needle for use in connection with a coiled record strip for both making 10 a record upon the edge of the strip and for reproduction of sound from the recording, and also to hold and guide the needle in contact and register with the edge of the strip during the travel of the coiled record strip beneath the 15 needle, the invention taking advantage of the spiral space or channel between the convolutions of the strip for the reception of a projection or arm disposed at one side of the needle to hold the latter in true register with the edge of the 20 strip.

A further object is to provide a needle having the above characteristics and which serves as a heat transfer medium to heat a strip and soften it sufficiently to receive a record impression from 25 the needle.

A further object of the invention is to provide means for recording sounds upon the comparatively narrow surface or edge of a tape strip such as an audible moving picture film whereby 30 the space on the film heretofore used for recording sounds by means of lights and shadows is conserved for providing larger pictures adapted to show minute details when projected on to a screen.

35 Another object of the invention is to provide means for recording feeble sound vibrations directly upon a substantially indurate durable record adapted for immediate use in reproducing the original sounds.

40 Other and further objects and advantages of the invention will be understood from the following detailed description reference being had to the accompanying drawings in which:

45 Figure 1 is a side elevation, partly in section, and showing a preferred embodiment of the recording means of this invention.

Figure 2 is a detail on an enlarged scale of certain of the parts shown in Figure 1 as applied 50 to the tape strip record of this invention for reproducing the sounds indented on the tape.

Figure 3 is a view similar to Figure 1 and showing a modification of the preferred means employed.

55 Figure 4 is an enlarged detail showing certain

portions of the mechanism of Figure 3 as applied to a flat disc for recording sounds thereon.

Referring now to the drawings for a more particular description and first to Figure 1, the preferred means employed includes a frame 10 which 60 may be formed annular in plan and to which is secured a housing 11 by means of screw threads 12 or the like. The frame and adjunct parts are adapted to have vertically reciprocating motions or vibrations and is prevented from horizontal movements by any suitable means such as the standards 13 extending through suitable apertures formed in the collar of the frame 10 and carried by a platform 14 or the like, the weight 65 of the housing and frame together with a later described mechanism resting upon a movable tape strip used in conjunction with the present invention.

The mechanism further includes a tape strip 70 guide 15 provided with a pair of upstanding ears 75 16 spaced apart a sufficient distance for the tape 17 to slide freely between the ears. Between the frame 10 and the lower edge of the housing 11 a diaphragm-disc 18 is positioned and adapted to have vibratory movements for purposes later described.

A hollow collar 19 is centrally attached to the bottom of the disc 18 as shown in Figure 1 and is provided with a sleeve 20, the exposed perimeter 80 of the latter being turned slightly inwardly as 85 at 21 for gripping a removable needle 22.

A coil 23 is positioned about the sleeve or in contact therewith and is adapted to heat it, whereby the heat is transferred to the needle and tape strip 17, the coil 23 being in electrical communication with a source of electrical energy such as the battery 24 through circuit wires 25, the circuit including a fuse 26 and a rheostat 27 for selectively varying or regulating the temperature 90 applied to the work.

Within the housing 11 an electromagnet 28 is supported by any suitable means such as the stud bolt 29 and is in electrical communication with a microphone 30 through circuit wires 31 and a source of electrical energy such as the battery 32. 100

It will be understood that the needle 22, shown in Figure 1, may be of any desired configuration for recording purposes and that the tape strip 17 may be passed under the needle and in contact with it by any suitable means such as manually 105 or by means of a reeling device, not shown; further, that the microphone 30 is provided with a conventional carbon button and diaphragm.

In operation sounds generated adjacent the receiving horn 33 of the microphone 30 creates air 110

vibrations, in a well-known manner, causing the diaphragm of the microphone to vibrate and simultaneously electrically communicating and causing corresponding movements of the diaphragm 18 and needle 22 whereby a record of the sounds is intended or inscribed upon the tape strip 17 as the latter is moved.

As the tape starts to describe a recording movement the heat is applied to it for temporarily altering its substantially indurate character and recording the sound impulses thereon while the tape is in a softened condition or the like; whereupon the tape is permitted to regain its normal character as it moves away from the needle or inscribing means.

It will be understood that certain chemicals may be employed for softening the tape in lieu of heat being applied as above described, said chemicals preferably being susceptible of evaporation subsequent to use.

The above specifically described arrangement of parts is adapted to make direct vertical cuts or indentations upon the strip 17 and the means of this invention is also adapted to make lateral recording cuts upon disc records or tape strips as now to be described.

Referring to Figure 3, the needle 22' is removably carried in a shaft 40 by means of a set screw 41 and provided with a heating coil 23', circuit wires 25', a battery 24', rheostat 27' and fuse 26'.

The shaft 40 is removably attached to the armature 42 of an electro-magnet by means of a collar and set screw 43, the armature being provided with a coil 44 in electrical communication with a microphone 30' through circuit wires 31' and a battery 32'.

The coil 44 and armature is carried by a sleeve 45 pivotally positioned between the poles of a magnetized member 46, said pivot not being shown, whereby the point of the needle is adapted to vibrate laterally in alignment with and between the poles of the member 28' correspondingly with sound impulses imparted to the microphone 30' for recording from the latter.

It will be understood that the arrangement of parts shown in Figure 3 is adapted to record upon the edge of the tape strip shown in Figure 1 and when so used the tape strip guide 15 is employed. It will also be understood that the needle 22' will record sounds upon the flat disc record 46 shown in Figure 4 while the disc is rotated upon a turn-table 47 carried by a driven axle 48.

As best shown in Figure 2, the needle 22 may be provided with an elongated guide arm 50 particularly useful in transcribing coiled strip records for holding the point of the needle in operative position with respect to a record, the latter being attached to a removable hub 51, carried by a driven post or axle 52 of a turn-table 53 upon which the coiled strip 17 is positioned for transcribing purposes and it will be noted that the coiled strip record shown in Figure 2 may be repeatedly transcribed by inserting the guide arm 50 at any selected place between the coiled laminations of the record, the latter being so coiled that the start of the letter or record is adjacent the removable hub 51 and when used for transcribing purposes the needle 22 is so mounted and carried that it is adapted to have horizontal swinging movements, similar to the tone arm of a conventional phonograph, and in alignment with the turn-table for traveling outwardly away from the hub towards the end of the record or last outward turn of the coiled strip, the latter being flexible and permitting the insertion of the

arm 50 which guides the needle outwardly of the coil at times when rotary movements are imparted thereto. It will be understood that when used for transcribing purposes an amplifying horn is applied to and carried by the adjunct parts of the diaphragm 18 and needle 22, of Figure 2, no heat being applied to the needle during transcription of records. Also the transcription mechanism may include, if desired, electrical means as is apparent.

By means of the present invention letters and reports can be dictated and forwarded with a greater degree of accuracy and economy than heretofore and inflections of the voice noted whereby the emphasis applied to words is properly understood and appraised, the mechanism being more compact and easier to transport than the heretofore used correspondence dictating machines, typewriters and the like; the instant means being of light weight and of few and simple parts, is readily transportable by traveling salesman and the like. Where a large amount of letters are to be dictated the mechanism for driving or reeling the tape 17 may include an electrical motor, or the reeling device may be manually operated and it will be obvious that the tape 17 may be caused to travel by manual manipulation solely.

It is believed to be obvious that I have provided an economical means for forwarding and receiving communications and recording music and the like and from the foregoing description it is thought to be obvious that my invention is particularly well adapted for use by reason of the convenience and facility with which it may be assembled and operated and it will be noted that my invention is susceptible of some change and modification without departing from the principles and spirit thereof and for this reason I do not wish it to be understood as limiting myself to the precise arrangement and formation of the several parts herein shown in carrying out my invention in practice except as claimed.

I claim:—

1. A phonograph needle for coiled record strips, comprising a needle body having an end portion adapted to engage against the edge of the coiled record strip to transmit vibrations therefrom, and a guide member carried by the needle and extending in off-set relation therebeyond for engagement between the convolutions of the coiled record strip to hold the end of the needle in register with the edge of the strip when the coiled record strip is bodily turned.

2. A phonograph needle for coiled record strips, comprising a needle body having an end for contact with the edge of the record strip and having a laterally off-set arm extending beyond the needle for engagement between the convolutions of the coiled record strip to guide the needle over the edge of the strip when the latter is bodily turned beneath the needle.

3. A phonograph needle for coiled record strips susceptible to softening for recording when subjected to heat, comprising a heat transmitting needle body having a point for contact with the edge of a coiled record strip to transmit heat thereto and press a record groove therein, means for heating the needle body, and a guiding arm carried by the needle projecting at one side beyond the point thereof for engagement between the convolutions of the coiled record strip to hold the end of the needle in register with the edge of the strip.
